UNITED STATES PATENT OFFICE.

CHARLES L. RAGOT, OF KINGSBRIDGE, NEW YORK, AND LOUIS F. RAGOT, OF MILFORD, PENNSYLVANIA, ASSIGNORS TO RAGOT MOTOR CORPORATION, A CORPORATION OF NEW YORK.

ROTARY ENGINE.

Application filed September 9, 1919. Serial No. 322,620.

To all whom it may concern:

Be it known that we, CHARLES L. RAGOT, a citizen of the United States, and a resident of Kingsbridge, New York city, in the county of New York and State of New York, and LOUIS F. RAGOT, also a citizen of the United States, and a resident of Milford, in the county of Pike and State of Pennsylvania, have invented certain new and useful

10 Improvements in Rotary Engines, of which the following is a specification.

This invention is an improvement in rotary motors of that type in which the cylinders are arranged radially in respect to the axis of revolution and the pistons have members engaging with a track encircling said axis and at varying distances therefrom. An engine of that type is disclosed in our prior Patent 1,302,709 issued May 6,

15 20 1919 and certain features of our present invention are there broadly claimed.

As an important feature of our present construction we provide an inwardly facing track on each side of a single row of cylinders, each inwardly facing track being opposed by a smaller track parallel thereto and in the same plane and spaced radially therefrom a distance approximately equal to the diameter of a roller so that the pistons are controlled in their inward as well as their outward movements.

In connection therewith, we provide each piston and cylinder with co-acting key and keyway, thereby preventing rotation of the piston about its axis and also holding the roller axis at right angles to the planes of the tracks and insuring proper engagement of the rollers with the tracks.

The engine is provided with a distributor having two concentric tubes, one for the ingress, and the other for the egress of the motive fluid, and said tubes have ports alternately arranged in the same transverse plane so that the cylinders communicate first with one and then with the other tube during the revolution.

As one feature of our invention we provide an improved throttle construction involving a member axially movable in respect to the stationary distributor so as to permit either of said tubes to carry the incoming motive fluid and the other the exhaust, and thus control the direction of rotation of the engine.

In the accompanying drawings to which

reference is to be had, we have illustrated one embodiment of our invention, although it will be understood that we do not desire to be limited to the details of construction there illustrated except in so far as they are defined specifically in the appended claims.

In these drawings:—

Figure 1 is a transverse section at right angles to the axis of rotation, the three equal radial segments of the figure being taken on three separate planes.

Figure 2 is a central longitudinal section on a plane indicated by the line 2—2 of Figure 1.

Figures 3, 4, and 5 are sections on the lines 3—3, 4—4, and 5—5, respectively, of Figure 2, and

Figure 6 is a transverse section on the line 6—6 of Figure 5.

In the specific form illustrated, there is provided a stator casing including end walls or plates 10 and 11 spaced apart by a peripheral wall 12, the three walls being held rigid in respect to each other in any suitable manner, as for instance, by stay bolts 13. The end walls 10 and 11 have central cylindrical bosses, sleeves, or extensions 14, and 15, coaxial with the motor. Within the casing there is mounted a rotor including a sleeve or tubular body portion 16 coaxial with the motor and presenting an annular row of radially disposed cylinders 17 rigid therewith, and if desired, integral therewith. The rotor is journalled within the casing in any suitable form of bearings, as for instance, a pair of ball bearings 18 and 19 upon opposite sides of the row of cylinders and between the periphery of the tubular member or sleeve 16 of the rotor and the inner surface of the casing. The one end of this sleeve or body portion of the rotor is illustrated as being formed integral with an extension 20 projecting through the boss 15 on the end plate 11 of the casing and constituting a hollow shaft to which the mechanism to be driven by the rotor may be connected to the latter either internally or externally. This boss 15 is illustrated as being provided with a packing gland 21 encircling the hollow shaft 20 so as to make the interior of the casing substantially air and oil tight.

As important features of our improved motor, each cylinder is provided with a pair of longitudinally extending slots 22

along opposite sides facing in the direction of the axis of the motor and within each cylinder is a piston 23 having a spindle 24 parallel to the axis of the motor and 5 extending through these slots. Each of the end walls of the casing presents two parallel tracks 25 and 26 in the same plane and spaced a uniform distance apart. These tracks are at varying distances from 10 the axis of the rotor and are preferably elliptical so as to provide two outstrokes and two instrokes of each piston during a single revolution of the rotor. Each spindle 24 has a roller 27 upon each end thereof and 15 located between the corresponding pair of elliptical tracks. The diameter of each roller is but slightly less than the distance between the two tracks so that as the rotor turns, the rollers will engage only one 20 track of each pair at one time, depending on whether the piston is forced outwardly as during the power stroke or the piston is caused to move outwardly by rotating the motor by applying some power from the 25 outside. By this construction the pistons are positively guided and controlled to effect their outward and inward movements. As the main pressure of the rollers is 30 against the outer tracks 25 during the power stroke and the inner tracks 26 serve primarily to keep the pistons from falling inwardly and thus rattling or jarring when the rotor is turning without motive fluid, we find it desirable to make the outer tracks 35 of harder material. The main casing may be made of comparatively light material and may have the tracks 26 formed directly on the inner surfaces of the end walls 10 and 11 but the outer tracks 25 are preferably 40 formed on plates 28 of hardened steel or other suitable wear resisting material. These plates are shown as being clamped in position by the same bolts 13 which hold together the three main sections of the casing. 45

To prevent rotation of the pistons within their cylinders and to thereby hold the axes of the spindles at right angles to the planes of the tracks, the pistons and cylinders are 50 provided with coating keys and keyways. Each cylinder is shown as having a pair of oppositely disposed slots 29 extending lengthwise thereof upon opposite sides and spaced 90° from the slots 22, although one 55 such key and slot may be employed with a similar result. These slots 29 are preferably at the outer ends of the cylinders and beyond the slots 22 which latter are intermediate of the ends of the cylinders. Each 60 piston is shown to be of such length that the slots 22 are always completely covered, the outer ends of the pistons projecting beyond the outer ends of the slots 22 but this is not essential as long as the inner ends of the slots 22 are not uncovered by the piston

head which would provide an escape of motive fluid. Each piston at its outer end presents a pair of outwardly extending projections engaging in the slots 29. These are shown as formed of a transverse key 30 secured in a transverse groove in the outer end of the cylinder and of such length as to extend into the slots 29. Thus the engagement of this key with the slots 29 which constitute keyways, prevents any rotation of 70 the cylinder about its axis and as these keys and keyways are in line with the side thrust of the piston against the cylinder wall, they take up none of the said thrust leaving a 75 free movement of the piston to aline it- 80 self within the cylinder bore.

The boss or sleeve 14 of the casing has a transverse outer end wall 31 carrying a distributor projecting coaxially of the motor and spaced from the peripheral wall of the sleeve 14 and into the main sleeve or body 16 of the rotor. This distributor is illustrated as including two concentric tubes 32 and 33 rigid in respect to each other and coaxial but they may be eccentric with one another without impairing their performance. The body or sleeve 16 of the rotor has an annular series of radial ports 34, one connecting with the inner end of each cylinder. In the transverse plane of these cylinder ports 34 the outer tube 32 is provided with a pair of oppositely disposed ports 35 each of which may register with each port 34 during the revolution of the rotor. The inner tube 33 has a transversely extending branch passage 36 terminating in a pair of ports 37 in the same plane with the ports 35 and spaced midway between the latter. Thus during the rotation of the rotor, each cylinder port registers first with a port 35 100 and then with a port 37 and communicates with the interior of the tubes 32 and 33 alternately and twice during each rotation. 105

The boss or sleeve 14 of the casing has 110 a pair of passages or chambers 38 and 39 extending along the inner surface circumferentially thereof, as shown particularly in Figures 3 and 4. The passage 38 communicates with a motive fluid passage 40, which for purposes of description, may be considered as the inlet passage, while the passage 39 communicates with a similar motive fluid passage 41, which for present purposes may be designated as the exhaust passage. 115 The inner tube 33 of the distributor has a pair of branch passages 42 and 43 in the same transverse planes with the passages 38 and 39 and extending through the outer wall of the outer tube 32 without communicating with the interior of said outer tube. The outer tube is illustrated as having a pair of ports 44 and 45 diametrically opposite to the branch passages 42 and 43 and also in the same transverse planes as the casing 120 passages 38 and 39. It will be understood, 125 in the same transverse planes as the casing 130 passages 38 and 39.

however, that the location of branch passages 42 and 43 may be at any position around the circumference of the said distributor, the same being true of the ports 44 and 45 and that they are shown to be all in the same longitudinal plane with ports 37 for convenience in illustration. Between the outer surface of the distributor and the inner surface of the casing part 14, there is provided a longitudinally slideable sleeve 46 constituting a throttle. This has a single port 47 which may register with either the port 44 or the port 45 and a pair of ports 48 and 49 for registry with the branch passages 42 and 43 of the inner tube of the distributor. These three ports in the throttle are so positioned that when the throttle is moved endwise toward the left from the position shown in Figure 2, the port 47 will register with the port 44 and connect the interior of the outer tube of the distributor with the casing passage 38. At the same time the port 49 will register with the branch passage 43 of the inner tube and connect the latter with the casing passage 39. Assuming that the motive fluid be admitted through the inlet 40 it will flow along the casing passage 38 and through the ports 47 and 44 to the outer tube and from the latter through the ports 35 to the engine cylinder ports 34. At the same time the exhaust from other engine cylinders may flow through ports 37, inner tube 33, and branch passage 43 and port 49 to the casing passage 39 and thus to the exhaust, and there will result a rotation of the rotor in one direction. If the throttle be moved to the opposite limiting position, namely, toward the right from the position shown in Figure 2, the ports 45 and 47 will register and the port 48 will register with the inner tube passage 42. Thus the motive fluid entering the inlet 40 will flow direct to the inner tube and out through the ports 37 to the engine cylinders while the exhaust will flow through the ports 35 to the outer tube and thence through 45 and 47 to the outlet 41 and a rotation in the opposite direction will result. The same result will be obtained if the position of the throttle sleeve ports is reversed, that is, if the port 47 is located to register with branch passages 42, and 43, and ports 48 and 49 of the throttle are located to register with ports 44 and 45 of the outer tube 32. By holding the throttle in the intermediate position as shown in Figure 2, all the ports will be closed and the engine will remain at rest. It will of course be evident that the designation of the part 40 as the inlet and the part 41 as the exhaust is purely arbitrary as either part may serve either purpose. Any suitable means may be employed for operating this throttle sleeve 46 and limiting its motion. As shown, the casing ex-

tension 14 is provided with a longitudinal slot 50 through which extends a handle 51 rigid with the throttle sleeve. The length and position of this slot may be such that with the handle at one end, rotation in one direction will be secured and when at the other end, rotation in the opposite direction will result. This slot is preferably on the side of the casing opposite to the passages 38 and 39 as indicated particularly in Figures 3 and 4.

The engine above described may be employed in connection with various different motive fluids, as for instance, steam, compressed air, or water, and the rotor may be connected in any suitable manner, as for instance, by the hollow shaft 20 to any part which it is desired to drive. It will also be evident that by applying power to the shaft 20, the rotor may be mechanically operated and the mechanism may be used as a pump, compressor, or the like. The same general principles of construction may be applied to a two-cycle internal combustion engine by proper arrangement of ports, cooling means, ignitors, and other appurtenances of such an engine. The elliptical tracks provide for two instrokes and two outstrokes per revolution but it will be evident that tracks of other forms might provide a greater or less number of reciprocations per revolution with a corresponding change in the number and arrangement of the ports 35 and 37. By making the tracks alongside of the cylinders and projecting inwardly beyond the outer ends of the cylinders and pistons the latter deliver their power from points intermediate of their ends and the pistons are adequately and properly guided while the casing is of the minimum diameter which, as will be seen, is but slightly greater than the outside diameter of the rotor.

Having thus described our invention what we claim as new and desire to secure by Letters Patent is:—

1. In combination, a rotor having a plurality of cylinders bodily movable about the axis of rotation of the rotor, and an annular row of cylinder ports, one port for each cylinder, a stationary distributor including a pair of tubes, each provided with a plurality of ports arranged in the same circumferential path with the cylinder ports, each alternate one of said second mentioned ports communicating with one tube and the remaining ones communicating with the other tube stationary motive fluid supply and exhaust conduits, and an axially movable sleeve having ports for connecting either of said passages with either of said tubes.

2. In combination, a casing, a rotor mounted therein and having a row of radially disposed cylinders and an annular row

- of cylinder ports, one port for each cylinder, and a distributor rigidly secured to said casing including an inner tube and an outer tube, each provided with a plurality of ports arranged in the same circumferential path with the cylinder ports, each alternate port communicating with the inner tube and the remaining ports communicating with the outer tube, and means for controlling the delivery of motive fluid through either of said tubes, and the exhaust through the other.
3. In combination, a casing, a rotor mounted therein and having a row of radially disposed cylinders and an annular row of cylinder ports, one port for each cylinder, and a distributor rigidly secured to said casing including an inner tube and an outer tube, each provided with a plurality of ports arranged in the same circumferential path with the cylinder ports, each alternate port communicating with the inner tube and the remaining ports communicating with the outer tube, and an axially movable throttle sleeve for connecting either of said tubes to the source of motive fluid, and the other tube to the exhaust.
4. In combination, a casing having an axially extending sleeve at one end thereof, a rotor within said casing and having a tubular body portion, a distributor rigid with said sleeve and spaced from the wall thereof and projecting into said rotor body portion, and having a pair of longitudinally extending passages, said casing sleeve having an inlet and an outlet, and said rotor body portion having a row of cylinder ports and a tubular throttle member encircling said distributor within said casing sleeve and axially movable for controlling the flow of fluid from said inlet to either of said passages and the escape of exhaust from the other.
5. In combination, a rotor having a plurality of radially extending cylinders having their axes in the same plane at right angles to the axis of rotation of the rotor, each of said cylinders having a pair of diametrically opposed longitudinally extending slots in said plane and a second pair of diametrically opposed longitudinally extending slots in a plane including the axis of rotation, a piston within each cylinder, a pair of projections on each piston extending through the first mentioned slots to prevent rotation of the piston about its own axis, a spindle carried by each piston and projecting through the second mentioned slots, and rollers mounted on opposite ends of said spindle, and a stator having an inwardly and an outwardly facing track on each side of said row of cylinders and engaging with said rollers to effect the radial movement of the cylinders during rotation of the rotor.

Signed at New York, in the county of New York and State of New York, this 29 day of August A. D. 1919.

CHAS. L. RAGOT.
LOUIS F. RAGOT
